UNITED STATES PATENT OFFICE.

GENERAL R. REED AND JAMES H. MORGAN, OF GREENVILLE, TEXAS.

RAILROAD-FROG.

1,247,879.

Specification of Letters Patent. Patented Nov. 27, 1917.

Application filed June 4, 1917. Serial No. 172,711.

To all whom it may concern:

Be it known that we, GENERAL B. REED and JAMES H. MORGAN, citizens of the United States, residing at Greenville, in the county of Hunt, State of Texas, have invented a new and useful Railroad-Frog, of which the following is a specification.

The present invention appertains to railroad frogs, and aims to provide a novel and improved structure of that character which will give double service, to increase the life and usefulness of the frog, the parts thereof being reversible or invertible.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawing, wherein:

Fig. 1 is a plan view of the improved railroad frog.

Fig. 2 is a cross section on the line 2—2 of Fig. 1.

Fig. 3 is a plan view of the frog point spacer.

The frog point is of V-shape and embodies the converging side sections 1 of double ball or tread formation, each section having the opposite balls or treads 2 connected by a web 3. The adjacent portions of the sections 1 are set obliquely and fitted together snugly, as at 4, to provide the point proper.

The frog point projects within the throat 0 of the frog provided between the pair of frog rails 5, which have their terminals curved apart on divergent lines. Each of the rails 5 is of double ball or tread formation, having the opposite balls or treads 6 connected by an intervening web 7. The frog point, as well as the rails, are therefore reversible or invertible, the rails 5 being interchanged when reversed or inverted, and being duplicates of one another.

In order to rigidly hold the frog point and rails 5 in place relatively, a V-shaped spacer 8 is employed, having the diverging arms 9

which fit astride the frog point against the webs of the sections 1 between the balls 2 thereof. The arms 9 fit the webs 7 of the rails 6 between the balls thereof. The spacer 8 not only has the arms 9 providing supplemental spacers between the frog point and rails 5, but the crotch portion of the spacer 8 also serves to space the rails 5 apart beyond the point. Transverse bolts 10 extend through the webs 3 and 7 and through the spacer 8 for clamping all of said parts firmly together, to space the rails 5 from the frog point. It is also preferable to provide one or more additional spacers 11 between the rails 5.

The frog point and rails 5 are seated upon tie plates 12 extending transversely thereunder, and provided with upstanding lugs 13 for holding the parts in place thereon, the plates being secured upon the underlying ties by means of suitable spikes 14.

The main rails 15 of the track are attached to the frog point and rails 5 by means of suitable rail joints, and if the balls or treads 2 and 6 are made exceptionally wide, or wider than the balls or treads of the ordinary rails, then the rails 15 can be offset, as shown in Fig. 1, and the corresponding fish plates for the rail joints are then used.

With the present structure, the frog point can be loosened and inverted, and the rails 5 can also be inverted and interchanged, whereby when the balls or treads which are uppermost become worn out, the parts can be reversed to renew the life thereof, and thus double the usefulness of the frog. Furthermore, the entire structure can be turned upside down on the tie plates, without the necessity of separating the frog point and rails 5. The structure can be modified or altered within the scope of what is herein-after claimed, in adapting the same to various conditions, and to provide frogs of various types.

Having thus described the invention, what is claimed as new is:

A railroad frog embodying reversible interchangeable rails each having opposite balls, a reversible frog point projecting between said rails embodying converging side sections fitting together snugly and each having opposite balls, a V-shaped spacer fit-

ting astride the frog point and between said rails, the spacer fitting between the opposite balls of each rail and frog point sections, and securing means extending through the 5 rails, spacer and frog point to clamp them all together.

In testimony that we claim the foregoing

as our own, we have hereto affixed our signatures in the presence of two witnesses.

GENERAL B. REED.
JAMES H. MORGAN.
